UNITED STATES PATENT OFFICE.

SAMUEL E. DIESCHER, OF PITTSBURG, PENNSYLVANIA.

TUBE-MACHINE.

SPECIFICATION forming part of Letters Patent No. 650,894, dated June 5, 1900.

Application filed December 28, 1899. Serial No. 741,822. (No model.)

To all whom it may concern:

Be it known that I, SAMUEL E. DIESCHER, a citizen of the United States, residing at Pittsburgh, in the county of Allegheny and State of Pennsylvania, have invented or discovered certain new and useful Improvements in Manufacturing Pipes, of which improvements the following is a specification.

The invention described herein relates to certain improvements in the manufacture of seamless tubing, and has for its object the progressive reductions of the internal and external diameters of a hollow ingot, the reduction of such diameters at any one point being equal and simultaneous.

The invention is hereinafter more fully described and claimed.

In the accompanying drawings, forming a part of this specification, Figure 1 is a diagrammatic view illustrating the method of forming tubes. Fig. 2 is a view, partly in section and partly in elevation, illustrating the manner of placing the ingot on the mandrel and holding the same as against longitudinal movement. Fig. 3 is a top plan view of the portion of the apparatus shown in Fig. 2. Figs. 4 and 5 are transverse sections, the planes of section being indicated, respectively, by the lines IV IV and V V, Fig. 3. Fig. 6 is a view, partly in section and partly in elevation, showing the relative arrangements of the several stands of rolls. Fig. 7 is a sectional elevation, on an enlarged scale, of one of the rolls, its companion roll being shown in dotted lines; and Fig. 8 is an end view of the roll.

In the practice of my invention the ingots are suitably heated in a furnace 1, which is preferably so located with reference to the pipe-mill that the ingot will, as it is discharged from the furnace, roll or slide down the inclined plate or rails 2 into the receiving-cradle 3. This cradle is arranged so as to support the ingot with its axis in line or approximately in line with the axis of the mandrel 4. This mandrel, which extends continuously through the passes of the several stands of rolls, is supported centrally in said passes on the ends of pivotally-mounted arms 5. These arms are held in supporting position and returned thereto when shifted by the passage of an ingot by weights 6, con-

nected to extensions 7 of said arms. These extensions are at an angle to the arms, so that when the ends of the ingot move past the arms the latter strike the mandrel a sharp blow, so as to dislodge any scale or cinder resting thereon. The arms are prevented from moving beyond supporting position when shifted by the weights by suitably-arranged stops 8. As these supporting-arms alternate with the several stands of rolls, the mandrel will be efficiently supported at all times.

The mandrel is held from longitudinal movement during the sliding of an ingot thereon and the subsequent rolling of the ingot by suitable grippers or holding mechanisms to alternately hold the mandrel as against longitudinal movement. A convenient and desirable construction of gripping mechanism consists of a slotted plate 9, arranged in guides in the front standards of the holding-frame B. The sides of the mandrel are slotted, as at 11, for the reception of the prongs 12 of the plate 9. In order to permit of the sliding of the ingot onto the mandrel, the plate 9 is connected to a shifting mechanism, as the fluid-pressure cylinder 13. The mandrel is held from longitudinal movement while the holding-plate 9 is withdrawn by a supplemental gripper formed by the slotted plate 14, arranged in guides at the rear end of the holding-frame. In order to insure the engagement of the prongs of the supplemental gripper 14 with slots 15 in the mandrel simultaneous with the disengagement of the main or front gripper, the plate or gripper 14 is connected to one end of the lever 16 and the opposite end thereof is connected to the plate or gripper 9 or its actuating mechanism. By such connection the engagement of one or the other of the grippers with the mandrel is insured and the latter is prevented from longitudinal movement at all times.

When it is desired to place an ingot on the mandrel, the main or front grippers are lowered and the supplemental grippers raised to engage the mandrel, thus leaving the front end of the mandrel free. The pushing-fingers 17 and 18 are then moved forward, preferably by a fluid-pressure cylinder 19, so as to push the ingot from the cradle onto the mandrel. By reference to Figs. 4 and 5 it

will be seen that the upper finger will pass above the plate 9 when raised to engage the mandrel and that the finger 18 is made of such transverse dimensions that it will move 5 through the slot in the gripping-plate. This construction permits of the raising of the main gripper 9 after the rear end of the ingot has passed beyond, so that fingers can push the ingot into the bite of the first pair of reducing-rolls, the auxiliary grippers being lowered simultaneous with the raising of the main gripper.

While for convenience of illustrating and describing the reducing action of the rolls 15 the latter are represented in the diagrammatic view, Fig. 1, as horizontally arranged, as a matter of fact the rolls are arranged at or approximately at an angle of forty-five degrees, and the axes of one stand of rolls are 20 at an angle of ninety degrees to the axes of the rolls of the next adjacent stand. As it would be difficult to keep the housings in position on inclined foundations, the upper surfaces of the foundations or piers for the roll 25 and pinion housings are made horizontal for the reception of the bed-plates 26, as shown in Fig. 6, and the sides 27 of the roll and pinion housings are similar in construction. The desired inclination is obtained by forming 30 seats 28 on the bed-plates of different heights for supporting the sides 27 of the housing. By varying the relative heights of the seats any desired inclination of the housings may be obtained. By this arrangement of the rolls 35 every stand of rolls and the driving mechanism thereof is easily accessible and the reducing action of each pair of rolls is at right angles or approximately at right angles to that of the adjacent pair of rolls.

40 As it would be inconvenient and impracticable to arrange the first two or three stands of rolls C, D, and E sufficiently close to permit the simultaneous action of two of them on the ingot, they may be driven at the same 45 speed or, if desired, at gradually-increasing speeds. The remaining stands of rolls F G II, &c., are arranged so that two or more of them will act simultaneously on the ingot, and hence each stand of rolls is driven at a 50 speed higher than that of the preceding rolls proportional or approximately proportional to the reduction and consequent elongation effected by such pairs of rolls.

55 In the operation of continuous mills it has been found to be practically impossible to drive the several stands of rolls at exactly the properly-increased speed. Hence in rolling articles of small cross-section provision is made for a "looping out" of the article, 60 the rolls being by preference so adjusted as regards speed that the article will tend to loop out. By such proportioning of speed the article will not be subjected to extreme tension and the rolls will not slip on the article.

65 In rolling articles of large cross-section it is obvious that looping out cannot be resorted to, and hence to avoid the destructive slip-

ping of the rolls on the articles the reducing portion of the several rolls is formed in a collar 20, which while fitting sufficiently tight 70 on the roll-body 21 to prevent any wabbling will permit the rotation of the roll independent of the collar. The roll is provided with a peripheral shoulder 22, preferably formed integral with the rolls and having its face inwardly inclined or undercut. The collar is clamped between this shoulder and the inner end of a sleeve 23, which is slipped over the free upper ends of the rolls. The sleeve is moved along the roll to clamp the collar by 80 screws 24, passing through a ring 25, secured on the end of the roll. The ring, which is formed in two sections, fits in a peripheral groove formed in the roll near its outer end, as clearly shown in Fig. 7. The sleeve is 85 locked on the roll, so as to rotate therewith, by any suitable means—as, for instance, by a feather on one part engaging a groove in the other part. By setting of the screws the collar may be so clamped that under normal 90 conditions of reduction it will rotate with the roll, but will permit the roll to rotate independently when the ingot is not fed to the rolls sufficiently fast or there is other abnormal hindrance sufficiently great to overcome 95 the grip on the collar.

In order to prevent the squeezing out of the metal between the rolls or the formation of fins, the grooves in the collars are so shaped as to form oval passes, the greatest axis of 100 the oval being parallel or approximately parallel with the axes of the rolls, thereby affording spaces into which the metal can flow.

As will be clearly seen by reference to Fig. 1, the mandrel is divided as regards its diameter into a number of sections *c d e f*, &c., corresponding to the number of stands of rolls employed. The reduction in diameter of each section corresponds approximately to the reduction in the diameters of the passes 105 in the rolls, so that there is an approximately-equal reduction of the external and internal diameters of the ingot at each pass. By reference to Fig. 1 it will be seen that section *d* of the mandrel is smaller than section *c* and that section *e* is smaller than section *d*. This change in diameter is preferably abrupt and is made just in the rear of the bite or plane of reduction of each pair of rolls, so that the 110 article will move freely over the mandrel 115 from one point of reduction to the other. By the employment of a mandrel so constructed that the internal diameter of the ingot is equal to the external diameter of the mandrel only in planes which pass through the 120 axes of both rolls of the several stands, a minimum resistance is offered to the onward movement of the rolls. These planes of friction occur just where the onward push of the rolls is most effective and where the elongation of 125 the ingot will tend to move the metal forward along the ingot and away from such plane of friction.

As regards the interposition between the

operative face of the roll and the driving mechanism of the latter of a frictional device whereby the driving mechanism can operate independent of the operative portion of the roll, the invention is not limited to any particular kind of mill or to a mill for reducing any particular kind of article, as such features are applicable to continuous mills generally.

10 I claim herein as my invention—

1. In a mill for rolling pipe, the combination of a series of stands of rolls, arranged in a common line of feed, a mandrel extending through the passes of said rolls, main and auxiliary grippers operative alternately to grip the mandrel and means for pushing an ingot onto said mandrel, substantially as set forth.

2. A roll for continuous mills having in combination a collar forming the operative portion of the roll and means for holding the collar in frictional engagement with the roll as against a predetermined resistance, but

permitting the roll to move independent of the collar when such resistance is above the 25 predetermined amount, substantially as set forth.

3. In a mill for rolling pipe, the combination of a series of stands of rolls arranged in a common line of feed, a mandrel extending through the passes of said rolls, grippers engaging the mandrel and means for holding the mandrel stationary when the grippers are released, substantially as set forth.

4. In a rolling-mill, the combination of a 35 bed-plate having supporting portions or seats projecting different heights above the bed-plate and housings secured to said seats, substantially as set forth.

In testimony whereof I have hereunto set 40 my hand.

SAMUEL E. DIESCHER.
